CLAIM

The ornamental design for portable camera immobilizer, as shown and described.

DESCRIPTION

FIG. 1 is a perspective view of a portable camera immobilizer showing my new design;

FIG. 2 is a top plan view thereof;

FIG. 3 is a bottom plan view thereof;

FIG. 4 is a front elevational view thereof;

FIG. 5 is a right side elevational view thereof, the left side being a mirror image thereof;

FIG. 6 is a rear elevational view thereof; and,

FIG. 7 is a reduced perspective view thereof, the broken lines shown are for illustrative purposes only and form no part of the claimed design.
